Primary Examiner — Kelley Donnelly(74) *Attorney, Agent, or Firm* — Norton Rose Canada LLP(57) **CLAIM**

The ornamental design for a chair, as shown and described.

DESCRIPTION

FIG. 1 is a front perspective view of the chair.

FIG. 2 is a back perspective view of the chair.

FIG. 3 is a right side view of the chair.

FIG. 4 is a front plan view of the chair.

FIG. 5 is a left side view of the chair.

FIG. 6 is a back plan view of the chair.

FIG. 7 is a top plan view of the chair; and,

FIG. 8 is a bottom plan view of the chair.

The broken lines showing in FIGS. 2, 4, and 8 are for the purpose of illustrating the environment of the design only and form no part of the claimed design.
